UNITED STATES PATENT OFFICE

167,876

CASTER CUP OR SIMILAR ARTICLE

Betty Auer, Chicago, Ill.

Application September 27, 1950, Serial No. 12,363

Term of patent 14 years

(Cl. D10—6)

To all whom it may concern:

Be it known that I, Betty Auer, a citizen of the United States, residing at Chicago, in the county of Cook and State of Illinois, have invented a new, original, and ornamental Design for a Caster Cup or Similar Article, of which the following is a specification, reference being had to the accompanying drawings, forming a part thereof.

Fig. 1 is a top plan view of a caster cup or similar article showing my new design;

Fig. 2 is an elevational edge view of the caster cup; and

Fig. 3 is a cross sectional view taken on the line 3—3 of Fig. 1.

I claim:

The ornamental design for a caster cup or similar article, as shown.

BETTY AUER.
